UNITED STATES PATENT OFFICE.

FRANK PARIZEK, OF CHICAGO, ILLINOIS.

DESIGN FOR A LAMP.

Application filed October 18, 1923. Serial No. 7,541. Term of patent 7 years.

To all whom it may concern:

Be it known that I, FRANK PARIZEK, a citizen of the United States, residing at Chicago, in the county of Cook and State of Illinois, have invented a new, original, and ornamental Design for a Lamp, of which the following is a specification, reference being had to the accompanying drawing, forming part thereof.

Fig. 1 is a top view of a lamp showing my new design; and

Fig. 2 is a side elevation thereof.

I claim:

The ornamental design for a lamp as shown.

FRANK PARIZEK.
